COMBINED TABLE AND CHAIR FOR A CHILD

Evert C. Weidner, 118 S. Race St.,
Kennett Square, Pa. 19348

Filed June 20, 1968, Ser. No. 12,457

Term of patent 14 years

Int. Cl. D6—01

U.S. Cl. D15—1

FIG.1

FIG.2

FIG.3

FIG.4

FIG.5**FIG.6****FIG.7****FIG.8**FIG. 1 is a perspective view of a combined table and chair for a child showing my new design, with the folding table member in exploded relationship;

FIG. 2 is a perspective view from the opposite side and with the unit rotated 90° counter-clockwise;

FIG. 3 is a perspective view taken from the bottom right of FIG. 2;

FIG. 4 is a sectional view on line 4-4 of FIG. 2;

FIG. 5 is a perspective view similar to FIG. 1 with the folding table member in assembled position;

FIG. 6 is a front elevational view;

FIG. 7 is a top plan view; and

FIG. 8 is a perspective view of the unit as shown in FIG. 2, with the apertured member as its base.

I claim:

The ornamental design of a combined table and chair for a child, as shown,
